Primary Examiner — Khawaja Anwar*Assistant Examiner* — Julice Seung Eun Oum(74) *Attorney, Agent, or Firm* — Paratus Law Group, PLLC(57) **CLAIM**

The ornamental design for a ladder and slide toy as shown and described.

DESCRIPTION

FIG. 1 is a front, bottom and left side perspective view of a ladder and slide toy showing my new design;
FIG. 2 is a rear, bottom and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is a front, bottom and left side perspective view of a state in use.

The broken lines in the drawings are for the purpose of illustrating portions of the ladder and slide toy that form no part of the claimed design.

1 Claim, 9 Drawing Sheets(56)
